FOLDABLE CARDBOARD BOX

Ralph F. Smart, St. Louis, Mo., assignor to Meade
Hyndman, Highland, Ill.

Application February 22, 1943, Serial No. 476,695

1 Claim. (Cl. 229—39)

This invention relates to foldable cardboard boxes.

An object of the invention is to provide an improved foldable cardboard box composed of a unitary or one-piece cardboard blank of novel construction and form including two complementary side walls and two complementary end walls, all of said walls having their lower edges in alignment with each other, tabs having aligned hinges integrally connecting them with the lower edges of said respective walls and being simultaneously foldable along said aligned hinges upon said respective walls by a single folding operation, means for interlocking and overlapping two of said tabs that are connected with two opposed complementary walls to form and provide a bottom for the box, and flaps having hinges integrally connecting them with said interlocking tabs fastened to the underside of an adjacent one of said tabs that are hinged to an adjacent wall portion, said tabs and said hinge connections being arranged so that the box may be opened, and held open when said tabs are interlocked, and may be refolded when said tabs are released from interlocking engagement.

Another object of the invention is to provide a foldable cardboard box composed of a blank of the form and construction already mentioned and more specifically described hereinafter and illustrated in the annexed drawing, whereby the boxes may be assembled in quantities more rapidly and at less cost than boxes composed of blanks of different form and construction.

Other objects will be apparent from the following description, reference being made to the annexed drawings, in which—

Fig. 1 is a plan view of an extended and unfolded blank for making a box in accordance with this invention.

Fig. 2 is a plan view showing the tabs of the blank as initially folded and superimposed upon the inner surfaces of the wall portions of the blank with which said respective tabs have integral connection.

Fig. 3 is a plan view similar to Fig. 2 showing hinged flaps of the bottom wall forming tabs folded upon the tabs proper to expose margins of the folded portions of the flaps for attachment to adjacent end wall tabs when the wall portions having said adjacent tabs and flaps are properly folded for each attachment.

Fig. 4 is a plan view showing one side of the completely folded box blank after the tabs and flaps have been permanently or integrally attached.

Fig. 5 is a plan view looking into the box, showing the tabs and flaps in intermediate positions before the box is completely opened.

Fig. 6 is a similar plan view looking into the box, showing the tabs and flaps in positions during movement thereof to properly interlocked positions of the tabs for forming the bottom wall of the box.

Fig. 7 is a plan view showing the inside of the completely opened box.

Fig. 8 is a bottom plan view of the outside of the box completely opened.

Fig. 9 is an enlarged sectional view on the line 9—9 of Fig. 7.

15 The blank of which the box is made is composed of cardboard or the like and is a unitary or one-piece structure. The unitary or one-piece blank is elongated and provided with transverse score lines 1, 2, 3 and 4 along which the blank is folded. These transverse score lines divide the blank into two complementary side walls 5 and 6, two complementary end walls 7 and 8, and an attaching tab 9.

20 The vertical width of the side and end walls is uniform. A longitudinal score line along the lower edges of said side and end walls forms hinges 10 integrally uniting the side walls 5 and 6 with bottom wall forming tabs 11 and 12, and integrally uniting the end walls 7 and 8 with tabs 13 and 14 for attaching the end walls to foldable flaps integral with the tabs 11 and 12. All of the hinges 10 are longitudinally aligned so that a single straight score line parallel with the upper edges of the walls 5, 6, 7 and 8 provides said 25 hinges. The bottom wall forming tabs 11 and 12 are formed with interengaging notches 15 and 16, respectively, in their free edges about midway of their ends so that, when the blank and tabs are properly folded and properly attached, as shown 30 in Fig. 4, the box may be opened and the bottom wall forming blanks 11 and 12 automatically interlocked approximately at the center of the box (Fig. 7) to provide a completed box. That is, the bottoms of the two interengaged notches 15 and 35 16 are at the center of the box bottom. These notches constitute means for interlocking and preventing relative sliding of the two tabs 11 and 12, and thereby prevent folding or collapse of the box until said notches are disengaged from each 40 other, and also hold the ends of the two tabs 11 and 12 in fixed positions under the respective flaps 17 and 19 and across the hinges 18 and 20 when the box is open. Different positions through 45 which the tabs are moved during their movements from folded position of the box to the

50 55

positions they occupy when the box is opened are shown in Figs. 5 and 6. The tab 11 is integrally united with a flap 17 by a hinge 18 extending from intersection of the hinges 1 and 10 to the notch 15 approximately midway of the length of the tab 11. And the tab 12 is integrally united with a flap 19 by a hinge 20 extending from intersection of the hinges 3 and 10 to the notch 16 approximately midway of the length of the tab 12.

After the blank has been formed to include these parts and these features, all of the tabs 11, 12, 13 and 14 may be folded at a single operation to superposed positions on the walls 5, 6, 7 and 8, respectively. The box blank is specially designed and constructed so that all of the tabs may be folded in this manner by a single operation and simultaneously. When the tabs are folded to superposed positions upon the walls of the blank, they occupy the positions shown in Fig. 2. Next, the flaps 17 and 19 are folded along the hinges 18 and 20, respectively, and superposed on the tabs 11 and 12. Then, cement or glue is placed upon exposed surfaces of tabs or flaps which are to be attached and which will overlap each other after they have been attached. For instance, the inner surface of the end portion of the side wall 5 which is to be attached to the tab 9, or the outer surface of said tab 9, may be provided with a coat 21 of cement or glue; the flap 17 or the tab 13, which are to be attached together in overlapping position, may be provided with a coat 22 of cement or glue; and the tab 14 or the flap 19, which are to be attached together in overlapping position, may be provided with a coat 23 of cement or glue.

Next, the wall 8 is folded along the hinge 3 to superpose the tab 14 on the lower margin of the flap 19, and the wall 5 is folded along the hinge 1 to superpose the flap 17 on the tab 13 and to overlap the flap 19. When thus folded, the parts occupy the positions shown in Fig. 4. Suitable pressure is applied to cause the coats of glue or cement 21, 22 and 23 to attach the adjacent overlapping flaps and tabs, leaving the blank or box folded flatwise and ready to be opened by movement through the positions shown in Figs. 5 and 6 to the final interlocked positions shown in Figs. 7, 8 and 9.

When the box is opened by movement of the parts through the positions shown in Figs. 5 and 6 to the final positions shown in Figs. 7 and 8, the tabs 11 and 12 cross each other at the notches 15 and 16, and said tabs 11 and 12 are interlocked at said notches. In this crossed and interlocked arrangement, the end portion of the tab 11 opposite from the flap 17 extends under the flap 19 which has integral or permanent connection with

the underside of the flap 14 by the attaching glue 23, and thereby sustains most of the weight of the contents of the carton at this end. The end 5 of the flap 12 opposite from the flap 19 extends under the flap 17, which is integrally or permanently attached to the underside of the flap 13 by the attaching glue or cement 22, and which is thereby strengthened and reinforced to sustain the weight of the contents of the carton at this 10 end. Both tabs 13 and 14 are above the respective flaps 17 and 19, respectively, and are within the box.

From the foregoing disclosure, it is evident that my improved carton may be assembled in minimum time, thereby substantially reducing the cost 15 of assembly below the cost of assembling boxes made of other types of blanks. The wall forming elements that are within the open carton and which sustain and support the weight of the contents are integrally or permanently united with the walls of the carton along the hinge lines 10. The tabs that form the bottom wall of the carton have portions interlocked that are integrally united and hinged to opposite side walls, and the 20 hinged end flaps of said interlocked tabs are permanently attached to the undersides of tabs that are integral with the end walls. This not only facilitates and expedites folding the blank as required to provide the carton, but also constitutes a reinforced and strengthened structure that will 25 sustain the weight of any contents for which the carton is designed.

I claim:

A foldable cardboard box composed of a one-piece cardboard blank including two opposite complementary side walls and two opposite complementary end walls integrally hinged together in endwise series by parallel transverse corner hinges, two complementary tabs having aligned 35 hinges integrally connecting them with the lower edges of said respective side walls and two complementary tabs having aligned hinges integrally connecting them with the lower edges of said respective end walls whereby all of said tabs may be folded upon said respective walls when said walls are flatwise, flaps having hinges integrally connecting them with said first named two tabs, and means attaching said flaps to the undersides of said second named two tabs, said first named two tabs having interengagable notches intersecting and curving away from the ends of said last named hinges for interlocking said first named two tabs and holding the ends thereof in fixed positions under said respective flaps and across the said hinges of said flaps and also vertically below said second two tabs when the box 40 is open.

RALPH F. SMART.
